UNITED STATES PATENT OFFICE.

CHARLES L. BRALEY, OF CHICAGO, ILLINOIS, ASSIGNOR OF ONE-HALF TO CHARLES F. NOELZGER, OF CHICAGO, ILLINOIS, AND OF ONE-HALF TO THE AMERICAN LAUNDRY MACHINERY COMPANY, OF CINCINNATI, OHIO, A CORPORATION OF OHIO.

LAUNDRY APPARATUS.

Application filed August 3, 1923. Serial No. 655,459.

To all whom it may concern:

Be it known that I, CHARLES L. BRALEY, a citizen of the United States, residing at Chicago, county of Cook, State of Illinois, have invented certain new and useful Improvements in Laundry Apparatus, of which the following is a specification.

This invention relates to improvements in laundry apparatus, being a development of 10 and improvement of the apparatus of the application No. 374,393, filed April 16, 1920.

The main objects of this invention are:

First, to provide an improved laundry apparatus by means of which work may be 15 effected with a minimum of manual effort on the part of the operator.

Second, to provide an improved laundry apparatus by means of which individual or family laundry may be effectively and 20 economically done.

Third, to provide an improved laundry apparatus having these advantages which is of large capacity, requires few operators and may be compactly arranged.

Objects pertaining to details and economies of construction and operation will 25 definitely appear from the detailed description to follow.

I accomplish the objects of my invention 30 by the devices and means described in the following specification. The invention is clearly defined and pointed out in the claims.

A structure which is a preferred embodiment of my invention is clearly illustrated in 35 the accompanying drawing forming a part of this application, in which:

Fig. I is an end elevation of a laundry apparatus embodying the features of my invention, certain parts being shown partially 40 broken away, one of the washing machines being shown in charging position and the other in discharging position.

Fig. II is a detail side elevation showing 45 parts of two units, the machine of one unit being shown in discharging position and of the other in upright or operative position.

Fig. III is a vertical section through one 50 of the washing machines in discharging position, the washing cylinder being shown in closed position by dotted lines.

In the drawings similar reference numerals refer to similar parts in all of the views.

Referring to the drawing, my improved laundry apparatus is preferably construct-

ed as separate units, as many units being 55 joined together as may be desired. Each unit comprises a pair of washing machines mounted on suitable frames designated generally by the numeral 1, these frames being made up in the structure illustrated of 60 pipes or tubing framework mounted upon the bases 2. The unit frames are connected by top cross members as 3 and constitute supports for the water supply tanks 5 and 6, one tank in the embodiment illustrated 65 being a hot water tank and the other a cold water tank. When a plurality of units is employed they are preferably connected as indicated in Fig. II.

The drain pipes 7 are mounted on the 70 bases 2 and provided with a catch basin 8 for each washing machine. The washing machines comprise the cylindrical tanks 9 which are rotatably mounted on the frames, that is, they are mounted for tilting adjustment thereon so that they may be swung to upright operative position to facilitate the discharge of the laundry therefrom. The washing machines are mounted in an ele- 75 vated position on the frames. 80

These tanks are provided with hoppers 10 preferably arranged with one side wall as 10' tangentially of the wall of the tank, see Fig. III. The washing cylinder 12 is rotatably mounted within the tank, each cylinder being provided with suitable driving means comprising, in the structure illustrated, a motor 11 and driving connnections 85 designated generally by the numeral 12.

The cylinder is provided with a door 13 90 which is arranged so that when open it rests upon the tangential side of the hopper and constitutes a chute or discharge member over which the laundry may be drawn from the cylinder. 95

The tank 9 is provided with a discharge or drain valve 14 controlled by the rod 15, this valve being adapted to discharge to the catch basin 8 when the tank is in upright or operative position. The supply tanks 5 100 and 6 are provided with valves 16 and 17 which are positioned to discharge into the hopper when the tank is in upright position. The valve rod 15 projects outwardly so that the operator on the platform 18 can 105 easily manipulate the same. This platform is carried by brackets 19 on the supporting frame.

In practice I preferably arrange these units in series, as stated, it being practical for one operator to attend to a number of machines.

- 5 Tracks 20 are provided at the outside of the frame and are accessible to the platforms 18 so that the laundry may be delivered to the machines in bags or containers 21 by means of the tracks, the operator being merely required to remove the bag from the carriage on the track, dump the same into the washing machine, the door being then open as indicated by dotted lines in the right hand machine of Fig. I, introduce the water through the valves 16 and 17 as may be desired, and start the motor. On completion of the washing operation, or when it is desired to change the water, the water is drawn off through the valve 14.
- 10 When the washing is completed the laundry is discharged from the machines by tilting the tank to the position shown at the left hand of Fig. I and in Fig. III. The laundry may be discharged direct to the extractor shown at 22, this extractor being mounted on a truck or carriage 23 traveling on the ways 24 mounted on the bases 2, so that the extractor may be positioned to receive the laundry direct from the machine.
- 15 20 This avoids the handling of the heavy wet laundry, it only being necessary to drag the same from the cylinder, the hopper and the washing cylinder door constituting chute members over which the laundry is drawn.
- 25 30 This avoids the handling of the heavy wet laundry, it only being necessary to drag the same from the cylinder, the hopper and the washing cylinder door constituting chute members over which the laundry is drawn.
- 35 40 The extractor is provided with a waste discharge 25 having a pivot section 26 adapted to be swung into engagement with the connections 27 on the waste pipe 7. This permits the moving of the extractor from machine to machine and its operation in receiving position.

I preferably provide a track 28 between the ranks of washing machines so that all the operator of the extractor has to do is to position the extractor, haul the laundry into the extractor as we have described, remove the laundry from the extractor, place it in bags 29 and attach the bags to the carriage 30 and place on the track. The track is preferably inclined so that no means are required to propel these carriages 30 away from the extractor.

With the parts thus arranged three operators can operate a number of machines with comparatively little manual effort. Women operators may be employed on the platforms for charging, and controlling the water in the operation of the machines as the operations here require but little strength.

60 65 I have illustrated and described my improvements in an embodiment which I regard as very desirable. I have not attempted to illustrate and describe certain other embodiments or adaptations which I contemplate as I believe the disclosure made

will enable those skilled in the art to which my invention relates to embody or adapt the same as may be desired.

Having thus described my invention what I claim as new and desire to secure by Letters Patent is:

1. In a laundry apparatus, the combination with a supporting frame, of a cylindrical tank mounted for tilting adjustment in an elevated position on said supporting frame and provided with a hopper, one wall of the hopper being tangentially disposed, a washing cylinder rotatably mounted within said tank and provided with a door adapted when open to lie on the tangential wall of said hopper facilitating the discharge of the washing cylinder when the tank is tilted to bring the hopper to horizontal discharging position, a supply nozzle positioned on said frame above said tank to deliver to the hopper thereof when the tank is in upright operative position, a drain valve at the bottom of said tank, and a waste pipe disposed below said tank and provided with a catch basin to which said drain valve delivers.

2. In a laundry apparatus, the combination with a supporting frame, of a cylindrical tank mounted for tilting adjustment in an elevated position on said supporting frame and provided with a hopper, one wall of the hopper being tangentially disposed, and a washing cylinder, rotatably mounted within said tank and provided with a door adapted when open to lie on the tangential wall of said hopper facilitating the discharge of the washing cylinder when the tank is tilted to bring to horizontal discharging position.

3. In a laundry apparatus, the combination of a tank mounted for tilting adjustment and provided with a hopper, a washing cylinder rotatably mounted within said tank and provided with a door hinged to the cylinder to swing outwardly against one wall of said hopper facilitating the discharge of the washing cylinder when the tank is tilted to discharging position, a supply nozzle positioned to deliver to the hopper when the tank is in upright operative position, and a drain valve at the bottom of said tank.

4. A washing machine comprising a tank mounted for tilting adjustment and provided with a hopper adapted as a discharge chute when said tank is tilted, and a washing cylinder rotatably mounted within said tank and provided with a door adapted when open to rest within and complement said hopper.

5. In a laundry apparatus, the combination of a washing machine comprising a tank mounted in elevated position for tilting adjustment and provided with a hopper adapted as a discharge chute when the tank is tilted, a waste pipe disposed below said

5 tank, a drain valve at the bottom of said tank adapted to deliver to said waste pipe when the tank is in upright position, a portable extractor adapted to be positioned below said hopper when the tank is tilted to discharging position so that the laundry may be discharged directly from the washing machine to the extractor, and a waste connection for said extractor adapted to be 10 adjusted to deliver to said waste pipe when the extractor is in position to receive the laundry from said washing machine.

6 6. In a laundry apparatus, the combination of a washing machine mounted in an 15 elevated position and adapted to be adjusted to facilitate the discharging of the laundry, a portable extractor adapted to be positioned to receive the laundry from the washing machine, a waste pipe, a drain valve for 20 said washing machine adapted to deliver to said waste pipe, and an adjustable waste connection for said extractor adapted to be connected to said waste pipe when the extractor is in position to receive the laundry 25 discharged from said washing machine.

7 7. In a laundry apparatus, the combination of a washing machine, a portable extractor adapted to be positioned to receive the laundry from the washing machine, a 30 waste pipe, a drain valve for said washing machine adapted to deliver to said waste pipe, and an adjustable waste connection for said extractor adapted to be connected to said waste pipe when the extractor is in 35 position to receive the laundry discharged from said machine.

8 8. In a laundry apparatus, the combination of a washing machine, a portable extractor adapted to be positioned to receive the laundry from the washing machine, a waste pipe for said washing machine, and an adjustable waste connection for said extractor adapted to be connected to said 40 waste pipe when the extractor is in position to receive the laundry discharged from said machine.

9 9. In a laundry apparatus, the combination with a plurality of washing machines, a waste pipe, discharge valves for said washing machines adapted to deliver to said waste 50 pipe, a portable extractor adapted to be positioned relative to said washing machines to receive the laundry discharged therefrom, and a waste connection for said extractor comprising a pivoted discharge member, said waste pipe being provided with coupling members with which said extractor dis-

charge member may be engaged when the extractor is in position to receive the laundry from one of said washing machines.

10 10. In a laundry apparatus, the combination with a plurality of washing machines, a waste pipe for said washing machines, a portable extractor adapted to be positioned relative to said washing machines to receive the laundry discharged therefrom, and a waste connection for said extractor comprising a pivoted discharge member, said waste pipe being provided with coupling members with which said extractor discharge member may be engaged when the extractor is in position to receive the laundry from one of said washing machines.

11 11. In a laundry apparatus, the combination with a plurality of washing machines, a waste pipe for said washing machines, discharge valves for said washing machines adapted to deliver to said waste pipe, and a portable extractor adapted to be positioned relative to said washing machines to receive the laundry directly therefrom, said extractor being provided with a waste discharge adapted to be adjusted to deliver to said waste pipe when the extractor is in position to receive the laundry from one of said washing machines.

12 12. In a laundry apparatus, the combination with a plurality of washing machines, a waste pipe for said washing machines, and a portable extractor adapted to be positioned relative to said washing machines to receive the laundry directly therefrom, said extractor being provided with a waste discharge adapted to be adjusted to deliver to said waste pipe when the extractor is in position to receive the laundry from one of said washing machines.

13 13. The combination with a plurality of washing machines, a track disposed at the side of said machines, a plurality of waste connections for said washing machines, an extractor traveling on said track to be operatively associated with any one of the said washing machines so that the laundry may be discharged from the machines directly to the extractor, and a waste discharge for said extractor adapted to be operatively connected with the waste connection of the washing machine with which the extractor is then operatively associated.

In witness whereof, I have hereunto set my hand.

CHARLES L. BRALEY.
